UNITED STATES PATENT OFFICE.

FRANK H. NICHOLSON, OF WILKINSBURG, PENNSYLVANIA, ASSIGNOR TO THE UNION SWITCH AND SIGNAL COMPANY, OF SWISSVALE, PENNSYLVANIA, A CORPORATION OF PENNSYLVANIA.

RAILWAY-TRAFFIC-CONTROLLING APPARATUS.

Application filed July 6, 1922. Serial No. 573,100.

My invention relates to railway traffic controlling apparatus of the type comprising governing means on a train controlled by energy received on the train from the track-way.

One feature of my invention is the provision of apparatus of this character suitable for use on a railway the motive power of which is alternating current.

10 I will describe one form of apparatus embodying my invention, and will then point out the novel features thereof in claims.

In the accompanying drawings, Fig. 1 is a diagrammatic view showing one form of 15 train-carried apparatus embodying my invention. Fig. 2 is a diagrammatic view showing one form of trackway apparatus suitable for co-operation with the train-carried apparatus shown in Fig. 1. Figs. 3 20 and 4 are vector diagrams showing the voltages and currents and the phase relations thereof in portions of the apparatus of Fig. 1 under various conditions. Fig. 5 is a resonance curve.

25 Similar reference characters refer to similar parts in each of the views.

Referring first to Fig. 2, the reference characters 2 and 2^a designate the track rails of a railway along which traffic normally moves in the direction indicated by the arrow. These rails are divided by insulated joints 3 into a plurality of successive track sections, of which only one section X—Y is shown in the drawing. It is understood, 30 however, that in practice each track section will usually be provided with apparatus similar to that illustrated for section X—Y.

Located adjacent the entrance end of section X—Y is a signal S^a which, as here shown, is of the semaphore type adapted to indicate "stop", "caution" or "proceed" according to the position of the semaphore. The circuits for the control of this signal are not illustrated in the drawing for the reason that they form no part of my present invention, and it is sufficient to say that the signal is controlled in accordance with present day standard practice through the medium of the track relays which will 40 presently be referred to. The track section immediately to the right of section X—Y is provided with a similar signal S^b.

Track section X—Y is provided with an alternating current track circuit comprising

55 a transformer T^b the secondary 4 of which is connected across the track rails adjacent the exit end of the section and a track relay R^a having a winding connected across the rails adjacent the entrance end of the section. The primary 5 of transformer T^b is constantly supplied with alternating current 60 from a transmission line 7 to which such current is furnished by a generator 8.

Means are also provided for supplying the rails of section X—Y with a second alternating current which flows in the same direction in the two rails at any given instant, and which I will term the local current. For this purpose a resistance 9^a is connected across the rails adjacent the entrance end of the 65 section, a resistance 9^b is connected across the rails at an intermediate point in the section, and a third resistance 9^c is connected across the rails adjacent the exit end of the section. The local current is supplied by a 70 transformer T^b₁ the primary of which is connected with the transmission line 7 through a pole-changer 6 operated by signal S^b.

The supply of current from the secondary 12 of this transformer is controlled by relay 75 R^b in the following manner: When relay R^b is energized, the secondary circuit for transformer T^b₁ passes through wire 45, front point of contact 44 of relay R^b, wire 80 46, resistance 9^c, track rails 2 and 2^a, resistance 9^a, and wire 47 to the secondary of transformer T^b₁.

When track relay R^b is de-energized, the secondary circuit for transformer T^b₁ passes through wire 45, back point of contact 44, wire 48, resistance 9^b, 85 track rails 2 and 2^a, resistance 9^a, and wire 47 to secondary 12. It will be seen from the foregoing that when track relay R^b is energized local current is supplied throughout the length of the section X—Y, and this current is of what I will term "normal relative polarity" because signal S^b is then in either the proceed or the caution position.

When track relay R^b is de-energized, however, local current is supplied to the rails from resistance 9^a to resistance 9^b, and this current is of what I will term "reverse relative polarity" because signal S^b then indicates stop and so the pole-changer 6 has been 90 reversed.

It will be seen from the foregoing that the rails of section X—Y are supplied with two alternating currents. One of these I

will term the "track circuit" current, and inasmuch as this current is supplied from transformer T^B , which is connected across the rails, it follows that at any given instant 5 this current flows in opposite directions in the two rails. The other current, which I have termed the "local" current, is supplied by transformer T^B , and this current at any given instant flows in the same direction in 10 the two rails. Both the track circuit current and the local current are supplied from generator 8 and transmission line 7, and so these currents are of the same frequency, which, for the purposes of this disclosure I 15 will assume to be 60 cycles per second, but they are preferably displaced in phase by 90° by suitable means such as a reactor 49 in the track circuit between transformer T^B and the track. These two currents will hereinafter be referred to collectively as the 20 "train controlling currents".

The railway shown in Fig. 2 is of the electric propulsion type, the motive power of 25 which is alternating current. The motive power current is supplied by a generator 16, one terminal of which is connected with a third rail or trolley 17, while the other terminal is connected through a wire 18 with the middle point of an induction bond 19, the 30 terminals of which bond are connected with the track rails 2 and 2^a, respectively. In order to conduct the propulsion current around the insulated joints 3 without at the same time permitting the track circuit current 35 to flow past these joints, each location X, Y, etc., is provided with two inductive bonds 20. One of these bonds is connected across the rails on one side of the insulated joints, while the other bond is connected 40 across the rails on the other side of the insulated joints, and the middle points of the two bonds are connected together by a conductor 21. As is well understood, these bonds offer low impedance to propulsion current, because such current enters each bond at the outer terminals and leaves at the middle point or enters at the middle point and leaves at the outer terminals, so that the two halves of the bond neutralize each other with 45 the result that the impedance is substantially zero. The track circuit current attempts to enter each bond at one end and leave at the other, however, so that the bond offers considerable impedance to such current. The 50 propulsion current delivered by generator 16 differs in frequency from the train controlling current delivered by generator 8, and for the purposes of the present disclosure I will assume that the frequency of the 55 propulsion current is 25 cycles per second.

Referring now to Fig. 1, the train-carried equipment comprises two pairs of magnetizable cores 22^T mounted in front of the first 60 axle 50 and arranged transversely above the

two track rails 2 and 2^a, respectively, each of these cores being provided with a winding designated F^T . Located at some other point on the train, such as in the rear of the first axle, is another pair of magnetizable cores 70 22^L, located above the two rails 2 and 2^a, respectively, and disposed transversely with respect thereto, each of these cores carrying a winding designated F^L . The windings F^T , which I will term "track windings", are so 75 connected that the voltages induced therein due to current flowing in opposite directions in the two rails at any given instant are additive, and so it will be seen that track circuit current in the rails will induce current in the circuit including the windings F^T . These two windings I will hereinafter refer to collectively as the "track coil". The two windings F^L are so connected that the voltages induced therein by current flowing 80 in the same direction in the two rails at any given instant are additive, and so it will be seen that local current in the track rails will induce a voltage in the circuit including the windings F^L . These two windings I will 85 hereinafter refer to collectively as the "line coil". For present purposes I will assume that the only voltages induced in these coils are those induced due to the two train controlling currents although, as 90 will hereinafter appear, the coils also receive voltages due to the propulsion current.

The voltage induced in track coil F^T is applied to the grid or input circuit of an electron tube amplifier K^T_1 and the voltage induced in the local coil F^L is applied to the grid or input circuit of a similar electron tube amplifier K^L_1 . These two amplifiers I will term the first stage amplifiers. Each of these amplifiers comprises a tube or bulb 100 23 containing a filament 24, a grid 25 and a plate 26. The plate or output circuit for the track current amplifier K^T_1 supplies energy to the input circuit of a second stage amplifier K^T_2 , while the output circuit of amplifier K^L_1 supplies energy to the input circuit of a 105 second stage amplifier K^L_2 . These second stage amplifiers are of the same type as the first stage amplifiers, although they may differ slightly therefrom in certain electrical 110 characteristics. The output circuits of the second stage amplifiers K^T_2 and K^L_2 supply current to the two stator windings 27^T and 27^L respectively of an induction motor relay 115 E which also comprises a rotor 28 and a contact 29 operatively connected with the rotor. As here shown, each stator winding of this relay is included in a local circuit tuned to resonance at the frequency of the train controlling currents by a condenser 30.

The two train controlling currents in the track rails are of the same frequency but are displaced in phase by approximately 90°, and so it follows that the currents supplied to the windings of relay E are of the same 120

frequency but are displaced in phase by approximately 90° . This relay, then, will be energized in one direction or the other according as the pole-changer 6 of Fig. 1 is in one position or the other. Relay E controls suitable train governing apparatus which forms no part of my present invention and which consequently is omitted from the present disclosure.

10 The filaments 24 of the amplifiers K are heated by a battery 31, and as here shown they are all connected in series. This battery also serves to operate a motor M which in turn drives a generator G supplying direct current to the plate circuits of the several amplifiers as will hereinafter appear.

15 It will be apparent at once that voltages will be induced in the receiving coils F^T and F^L by the propulsion current in the track rails. This current has at least two components, viz, a fundamental of 25 cycles, and the third harmonic thereof which is of 75 cycles, and voltages due to both components will be induced in the receiving coils. The propulsion current may also include a "slot frequency" which is of a frequency considerably higher than the third harmonic. The fundamental or 25 cycle current is so large compared with the train controlling currents, 20 and the voltages which it induces in the receiving coils will be so high, that to avoid overwhelming or smothering the first stage amplifiers these voltages must be suppressed before they reach these amplifiers. The third harmonic or 75 cycle current will be much less in amount than the fundamental of the propulsion current, but it may be much greater than the 60 cycle train controlling currents, and its frequency is so near that of the train controlling currents that the presence in the windings of relay E of currents due to this harmonic must be minimized in order to prevent false operation of the relay. The voltages impressed on the 25 grid circuits of the first stage amplifiers by the 75 cycle harmonic will not be high enough to smother these amplifiers, but amplification of the 75 cycle voltage in the first stage must be minimized in order that the 30 second stage amplifiers will not be smothered by the 75 cycle output of the first stage amplifiers. In the present form of my invention, then, I have provided means between the receiving coils F and the first stage amplifiers K₁ for suppressing the 25 cycle propulsion current as well as any slot frequency which may exist due to this current, and other means between the first and second stage amplifiers for suppressing the third harmonic of the propulsion current. Before explaining these means, however, I will state what I have assumed that the voltage and current values of the propulsion energy may be.

35 I have assumed a value of 1000 amperes of

25 cycle propulsion current as the maximum amount of 25 cycle current flowing in one track, and inducing a 25 cycle voltage in the local coil F^L on the train. So long as this current divides equally in the two rails, no 25 cycle voltage will be induced in the track coil F^T .

40 I have assumed further that, on account of the auto-transformer effect of the impedance bonds 20, the normal unbalancing of the 75 cycle propulsion current will be very slight, and that in the event of a broken rail, or bond, with the attendant large unbalancing of this current, the train controlling circuits will be put out of operation by the blowing of fuses in transformer and track relay leads. Therefore, if an excessive amount of 25 cycle or 75 cycle voltage is present in the track coil F^T as well as the local coil F^L , due to a broken rail and an excessive unbalance of propulsion current, the train control equipment should be at stop on account of the opening of the track circuits, and no harm would result even if the amplifying apparatus were smothered by the excessive 25 cycle and 75 cycle voltages. It is essential, however, that under these conditions there shall be no false energization of the train control relay E by the 75 cycle voltages.

45 I have assumed, therefore, that the normal unbalancing of propulsion current, and the unbalancing due to a small displacement of the pick-up structure from the center of the track, will induce a voltage in the track coil F^T not greater than 15% of the voltage induced in the local coil by the entire propulsion current. That is, if the maximum voltage induced in the local coil by the propulsion current is 10 volts, then I have assumed that not more than 1.5 volts will be induced in the track coil F^T .

50 The same circuits and protective means, however, must be used in both track and local circuits of the receiving and amplifying apparatus, because there must be no phase splitting of the voltages from a single phase source delivered to the track and local receiving coils. Therefore, there must be no differences in the electrical characteristics of the two circuits from the receiving coils to the relay windings.

55 The amount of 75 cycle current present in a 25 cycle propulsion current is not definitely known, but I have reason to believe that on open circuit, the third harmonic voltage in railway generators may be as high as 3% of the fundamental voltage. It seems reasonable to suppose that the third harmonic current would be less than 3%, because the reactance of the load circuit at this frequency would be greater than at 25 cycles. There may be other factors, however, such as the magnetization of the transformers, etc., tending to produce a third harmonic current and I have therefore assumed a

value of 75 cycle current equal to 3% of the 25 cycle propulsion current. On this basis, for 1000 amperes of 25 cycle current, the 75 cycle current will be 30 amperes. The 75 cycle voltage delivered to the grid circuit of the first stage amplifier of the local phase by 30 amperes of track current is taken as the maximum third harmonic voltage to be handled by the amplifying apparatus. This voltage will be about 8 volts in the local phase, and according to my earlier assumption, about 1.2 volts in the track phase.

The normal value of 60 cycle train controlling current is taken as 1 ampere, and the 60 cycle voltage delivered to the grid circuit of the first stage amplifier as about 1 volt.

Referring now to Fig. 1, the local receiving coil F^L is provided with a circuit which includes, in series, a condenser 35, a reactance coil 34 and a second condenser 33. As shown in the drawing, a third condenser 32 is also connected across the terminals of coil F^L , but this condenser will be neglected for the present. The values of the elements constituting circuit $a-b-d-e$ are such that the circuit is resonant at or near the frequency of the train controlling currents, whereas the constants of the portion $d-e$ are so chosen that this portion of the circuit is resonant at the frequency of the fundamental of the propulsion current. The grid circuit of amplifier K^L_1 is connected at points d and e in the receiving circuit, and since that part of the receiving circuit which lies between points d and e is resonant at the fundamental frequency of the propulsion current, which I have assumed to be 25 cycles per second, the voltage drop across these points due to current of propulsion frequency induced in the receiving circuit will be minimum. Condenser 35 may be of an impedance having considerable value at 25 cycles, so that in effect at 25 cycles the complete receiving circuit presents a resistance of relatively small value in series with an impedance of relatively large value; and since the voltage taken out of this circuit for the grid of amplifier K^L_1 is obtained from across the resistance (33 and 34), this voltage is of relatively small value.

At the frequency of the train controlling current, which I have assumed to be 60 cycles, that portion of the receiving circuit lying between points d and e is an inductance, and the entire circuit may be so arranged that the value of this inductance at 60 cycles is considerably greater than the value of the impedance of this portion of the circuit at 25 cycles. Furthermore, since the complete circuit $a-b-d-e$ is resonant at 60 cycles, a relatively large amount of 60 cycle current will flow through the portion $d-e$. The 60 cycle voltage across points $d-e$ can therefore be very much greater than the 25 cycle voltage across this

branch; in other words, the voltage induced in the receiving circuit by the train controlling current is amplified while the voltage induced in this circuit by the fundamental of the propulsion current is suppressed.

The main purpose of the third condenser 32 is to act as a by-pass for currents induced in the receiving coil F^L by currents of relatively high frequency, such, for example, as the slot frequency of the propulsion generating equipment. Such currents are in a measure short-circuited by the condenser 32 so that a relatively large proportion of the high frequency voltage induced in the receiving coil F^L is consumed in overcoming the impedance of this coil. It follows that the slot frequency voltage or other high frequency voltage appearing across the points $d-e$ is relatively small. Condenser 32 may serve a further purpose in that it can be used to increase the amplifying ratio of the complete receiving circuit $a-b-c-d-e-f$. This result may be accomplished by making the circuit $a-b-c-f$ resonant at or near the frequency of the train controlling current and the branch $c-d-e$ resonant at or near the same frequency. Furthermore, by adjusting the circuit $a-b-c-f$ to resonance at a frequency a few cycles above the train controlling frequency and the branch $c-d-e$ to resonance at a frequency a few cycles below the same frequency, the complete circuit may be made considerably more stable with respect to changes in phase and amplifying ratio when subjected to changes in the frequency of the train controlling current.

Interposed between the track coil F^T and the first stage amplifier K^T_1 associated therewith, is another group of devices similar to those just described and operating in the same manner to transmit train controlling frequency to the amplifier and suppress certain frequencies due to propulsion current in the track rails.

The apparatus for suppressing the third harmonic of the propulsion current is as follows: Considering first the amplifiers for the local phase, it will be noted that the complete output circuit for amplifier K^L_1 includes two branches, the first comprising a condenser 37, a resistance 43, and a reactor 39, all connected in series. The second branch for this circuit includes a condenser 38 and a reactor 40 also connected in series. A non-inductive resistance 36 is included in series with both branches. The grid circuit for the second stage amplifier K^L_2 is connected across reactor 40 and includes a blocking condenser 42. The grid circuit for the first stage amplifier K^L_1 is connected with the point C in reactor 39 for reasons which will be explained hereinafter.

As hereinbefore stated, I have assumed that the 75 cycle voltage input to the first

stage amplifier may reach a maximum of 10 volts. The normal operating input voltage at 60 cycles will be about one volt. Consideration of the operating characteristics of the electron tube amplifier will show that the main problem is to so suppress this 75 cycle voltage that the operation of the second stage tube will not be smothered by the incoming 75 cycle voltage. That is, if any considerable amount of 75 cycle voltage is allowed to reach the second stage amplifier, its capacity will be almost entirely absorbed by the 75 cycle voltages and the relatively smaller 60 cycle voltage will not be able to retain control of the tube and the train governing relay operated therefrom. An input not to exceed ten volts can be carried by the first stage tube without serious interference with the 60 cycle control. Therefore, the 75 cycle voltage must be suppressed between the first and second stage tubes.

Referring to the circuit diagram, branch A—B—C—D, in the alternating current output circuit of the first stage tube is resonant at or near 75 cycles, and so this branch may be known as the 75 cycle branch. The parallel branch, A—E—D, is resonant at a lower frequency,—preferably lower than 60 cycles, and may be known as the 60 cycle branch.

Referring now to Fig. 4, which is a vector diagram for 60 cycles, the line A—D may represent the 60 cycle voltage across the two parallel branches A—B—C—D and A—E—D. Since the 75 cycle branch is resonant at or near 75 cycles, at 60 cycles the net impedance will be that of a capacity and a resistance, and the current will lead the voltage A—D. The current through the 75 cycle branch is represented by vector i_{ABD} . Similarly, the net impedance of the 60 cycle branch will be that of an inductance and a resistance, so the current in the 60 cycle branch will lag behind the voltage vector A—D, as shown by vector i_{AED} .

The two currents, i_{ABD} and i_{AED} combine to give i_t , which is the current through the resistance 36. The drop through this resistance is in phase with current i_t and is represented by vector A—P. At this point, there is a third current i_{PMN} which flows through the choke coil 41 and generator G to point D. This current represents a waste of energy, and is made as small as practicable by making the series impedance 41 as high as practicable.

The total current i_t is the geometric sum of the three currents just noted. The voltage drop through the tube K_1 is in phase with the total current, and is represented by vector P—O. The total alternating current voltage in the tube plate circuit is the geometric sum of the three voltages A—D, A—P, and P—O, which is equal to the vector O—D.

The grid voltage on the first stage tube is equal to the total voltage in the plate circuit, divided by the amplifying ratio of the tube, and its phase is 180° displaced from that of the plate circuit voltage. This grid voltage is represented by vector e_g .

Returning now to vector A—D, it will be seen that the flow of current i_{AED} through the circuit AED produces the voltage drop A—E across the condenser 38 and the voltage drop E—D across the reactor 40. The latter voltage is the grid input to the second stage tube. Likewise, the flow of current i_{ABD} through circuit A—B—C—D produces the voltage drop A—B across the condenser 37, the voltage drop B—B' across the resistance 43, and the voltage drop B'—C—D across the reactor 39.

It will be noted that a tap has been brought out on the reactor 39 in the 75 cycle branch. The value and direction of the voltage between this tap and the end of the coil is represented by vector C—D. It will be noted further that the voltage C—D is introduced into the grid circuit of the first stage tube, so that the voltage across C—D is always added geometrically to the input voltage e .

Returning now to the grid voltage required to produce the voltages represented by the vector diagram, it will be noted that the voltage C—D is in the same general direction, and is almost equal to the required grid voltage e_g . It is apparent that to obtain voltage e_g , the voltage e , of proper phase and amount must be added to voltage C—D. It is apparent further that voltage e is very much smaller than e_g , and that the greater share of the input grid voltage is supplied by the voltage C—D, or in other words by the voltage output of the tube itself. The circuit is, therefore, regenerative at 60 cycles.

The overall amplification of this circuit up to the input of the second stage tube is equal to the ratio of voltage E—D to e , and in the case illustrated by this vector diagram, the amplification is equal to 58.

Referring now to Fig. 3, which is the vector diagram showing the voltages and currents at 75 cycles, and starting with approximately the same value for the voltage A—D, it will be seen that both currents in the parallel branches of the load circuit now lag behind the voltage A—D. The current through the 75 cycle branch is considerably increased over that at 60 cycles because circuit A—B—C—D is near resonance at 75 cycles. The total current i_t is likewise considerably increased. The drop through the resistance 36 and the tube is given by vectors A—P and P—O, respectively, and the total voltage in the plate circuit is given as before by vector O—D. The grid voltage e_g is obtained as before by dividing the total alter-

nating current plate volts by the amplifying ratio of the tube.

It will be noted that the increased current through the 75 cycle branch, produces an increased voltage across C—D of the reactor, and furthermore, the phase of this voltage has shifted about 90° in a clockwise direction.

Proceeding as with the 60 cycle diagram, and subtracting vector C—D from vector e_g , it will be seen that the former no longer assists the vector e in supplying the necessary grid voltage e_g . It will be seen that at 75 cycles, the output of the amplifier is used to oppose the input, and the circuit is therefore degenerative at this frequency.

The overall amplification of the circuit at 75 cycles is equal to the ratio of E—D to e , and is very much smaller than at 60 cycles. Using the values given on this diagram, the amplification is equal to 3.29.

The selectivity of this circuit between 60 cycles and 75 cycles is equal to the ratio of the two amplification ratios, or using the values noted on the diagram, the selectivity is equal to $58 \div 3.29 = 17.6$.

Considering now some of the functions of the detail parts of this circuit, it will be apparent that resistance 43 may be used to determine the amount of current flowing in the 75 cycle branch. The amount of current flowing in the 75 cycle branch determines the voltage across C—D, which is the regenerative or degenerative voltage. Therefore, this resistance can be used to adjust the amount of regeneration or degeneration.

Resistance 36 has two functions. One function is to minimize changes in the voltage and vector relations in the circuit due to change of tubes. The internal impedance of the electron tube varies in different tubes of the same type. If the resistance of the load circuit, which includes resistance 36, is large compared with the internal impedance of the tube, then variations in the impedance of the tube will not have much effect upon the voltage or vector relations existing in the complete circuit.

The second function of resistance 36 is to determine the frequency at which the amplification ratio of the complete circuit is a maximum. In other words, this resistance can be used to determine within limits the frequency at which the circuit appears to be resonant.

Considering the vector diagram at 60 cycles, it will be noted that at frequencies higher than 60 cycles, vector C—D will rotate in a clockwise direction and increase in length. At frequencies lower than 60 cycles vector C—D will rotate in a counter-clockwise direction and will decrease in length. It is apparent that for frequencies a few cycles less than 60 cycles vector C—D is moving into a position in which a vector of

given length is most effective as a regenerative voltage because it is moving into a position of exact phase agreement with e_g . But opposing this effect is the shrinking in length of C—D, as it moves into phase agreement with e_g , and a consideration of all quantities involved will show that for a given output, e is the shortest when vector C—D stands a little above vector e_g , or about in the position shown by the present 60 cycle diagram. Now, if at 60 cycles the values of resistance, reactance, capacity, etc., are such that vector C—D coincides in phase with e_g at some frequency higher than 60 cycles vector C—D would occupy the position shown by the present diagram, which is the position of maximum regeneration. Therefore, the peak of the apparent resonant curve would occur at a frequency higher than 60 cycles.

The frequency at which vector C—D is most effective as a regenerative voltage depends largely upon the geometry of the triangle made up of voltages C—D, e_g , and e . More particularly it depends upon the angle θ between vectors C—D and e_g . This angle between C—D and e_g can be determined within certain limits by the length of vectors A—P and P—O, and this length can be determined or adjusted by adjusting resistance 36. Therefore, the frequency, near 60 cycles, at which maximum regeneration, and therefore maximum amplification, will occur, can be determined by the resistance 36.

As an illustration of the second function of resistance 36, suppose for the 60 cycle diagram vector A—P were increased in length until vector O—D were parallel to vector C—D. Then vectors e_g and C—D would coincide in phase, and vector e would be the arithmetical difference between these two vectors. Now at 62 cycles vector C—D has increased in length, and occupies the position shown by the present diagram. But test and calculations show that for this position and length of vector C—D the length of vector e is a minimum for a given output. Therefore, the regeneration is a maximum at 62 cycles and if there is not too great a change in the other parts of the circuit, the circuit amplification will be greatest at 62 cycles. In a similar way, vector A—P may be made so short and the angle between C—D and e_g made so great that maximum regeneration and maximum amplification will occur at 58 cycles.

With the values given on the vector diagram, the point of maximum amplification occurs at about 59 cycles. To bring the peak of the output curve at 60 cycles, resistance 36 should be increased in value. Fig. 5 is a resonance curve illustrating the values just referred to, and from which it will be seen that the resonance peak occurs at 59 cycles.

In any circuit used for signaling or train

- controlling purposes, in which there is an element used to protect against energization from a foreign source, it is essential that the failure of the protective element should detect itself by making the complete circuit inoperative. This requirement is met in the circuit shown. It will be noted that at 60 cycles the greater share of the required grid voltage e_g is supplied from the output of the 10 first stage tube, by the voltage C—D. If the protective circuit A—B—C—D opens, the voltage C—D becomes zero, and the required input voltage e must then equal the grid voltage e_g if the output is to remain constant. 15 If voltage e is limited, as it will be in the case of the train control circuit, not enough voltage will be applied to the grid of the first stage tube to keep the train control relay energized through the amplifying circuit. A stop signal will result.

If, under the conditions cited above, a large 75 cycle voltage is applied to the first stage tube, the operation of the second stage tube will be smothered by the 75 cycle output 25 of the first stage tube. The relay therefore will not pick up on an excessive amount of 75 cycle voltage.

If a small amount of 75 cycle voltage is applied to the first stage tube of one phase and the protective circuit of this phase only 30 is open, there will be some phase splitting of the input voltages to the track and local phases, and the relay may be provided with two currents separated in phase by approximately 50° . The protective circuit of one phase being intact, however, not enough 35 75 cycle energy will be delivered to the respective winding of the relay to cause it to pick up.

40 If both protective circuits are open, there will be no phase splitting of the 75 cycle input voltages, which are from a single phase source, and the relay will not be energized because the 75 cycle currents through its 45 windings are of the same phase.

Although I have herein shown and described only one form of apparatus embodying my invention, it is understood that various changes and modifications may be made 50 therein within the scope of the appended claims without departing from the spirit and scope of my invention.

Having thus described my invention, what I claim is:

- 55 1. Railway traffic controlling apparatus comprising means for supplying the trackway with alternating propulsion current and alternating train controlling current differing in frequency, traffic governing means on 60 a train, and apparatus on said train for supplying said traffic governing means with a resonant rise of voltage at the train controlling frequency and with a resonant decrease of voltage at the propulsion current frequency.

2. Railway traffic controlling apparatus comprising means for supplying the trackway with alternating propulsion current and alternating train controlling current differing in frequency, a coil on a train receiving voltages due to said trackway currents, traffic governing apparatus on the train supplied with voltage by said receiving coil, and a bypass across said receiving coil resonant at the propulsion current frequency.

3. Railway traffic controlling apparatus comprising means for supplying the trackway with alternating propulsion current and alternating train controlling current differing in frequency, a coil on a train receiving voltages due to said trackway currents, traffic governing apparatus on the train supplied with voltage by said receiving coil, a bypass across said receiving coil resonant at the propulsion current frequency, and a condenser for tuning said bypass and said receiving coil to parallel resonance at the train controlling current frequency.

4. Railway traffic controlling apparatus comprising means for supplying the trackway with alternating propulsion current and alternating train controlling current differing in frequency, a coil on a train receiving voltages due to said trackway currents, traffic governing apparatus on the train supplied with voltage by said receiving coil, an element interposed between said receiving coil and said governing apparatus and tuned to series resonance at the propulsion current frequency, and means for tuning said element and said coil to parallel resonance at the train controlling current frequency.

5. Railway traffic controlling apparatus comprising means for supplying the trackway with alternating propulsion current and alternating train controlling current differing in frequency, a coil on a train receiving voltages due to said trackway currents, traffic governing apparatus on the train supplied with voltage by said receiving coil, a bypass across said receiving coil resonant at the propulsion current frequency, and a second bypass across said receiving coil for shunting frequencies higher than either the propulsion or train controlling current frequencies.

6. Railway traffic controlling apparatus comprising means for supplying the trackway with alternating propulsion current and alternating train controlling current differing in frequency, a coil on a train receiving voltages due to said trackway currents, traffic governing apparatus on the train supplied with voltage by said receiving coil, a bypass across said receiving coil resonant at the propulsion current frequency, a condenser for tuning said bypass and said coil to parallel resonance at the train controlling current frequency, and a second bypass across said receiving coil for shunting fre-

quencies higher than either the propulsion or the train controlling current frequencies.

7. Railway traffic controlling apparatus comprising means for supplying the trackway with alternating propulsion current and alternating train controlling current differing in frequency, a coil on a train receiving voltages due to said trackway currents, traffic governing apparatus on the train supplied with voltage by said receiving coil, and means interposed between said coil and said apparatus for shunting from said apparatus voltage created in said coil due to said propulsion current.

15 8. Railway traffic controlling apparatus comprising a trackway, means for supplying thereto alternating propulsion current and alternating train controlling current differing in frequency, a train provided with means for receiving voltages due to said trackway currents, traffic governing mechanism on said train, a first stage amplifier and a second stage amplifier interposed between said receiving means and said governing mechanism, apparatus located between said receiving means and said first stage amplifier for suppressing voltage due to the fundamental of said propulsion current, and other apparatus located between said first and second stage amplifiers for suppressing voltage due to the third harmonic of said propulsion current.

25 9. Railway traffic controlling apparatus comprising a trackway carrying currents differing in frequency, a train carried coil receiving voltages due to currents in the trackway, governing apparatus on the train supplied with voltage by said coil, and a by-pass across said coil resonant at the frequency of one of said trackway currents.

35 10. Railway traffic controlling apparatus comprising a trackway, means for supplying thereto alternating propulsion current and alternating train controlling current differing in frequency, a train provided with a coil receiving voltages inductively from said trackway currents, an amplifier on said train having an input circuit supplied with voltage by said coil, a condenser and a reactor connected in series across said input circuit, a second condenser interposed in said circuit between said coil and the point at which said reactor is connected with the circuit, and train governing means controlled by the output circuit of said amplifier.

45 11. Railway traffic controlling apparatus comprising a trackway, means for supplying thereto alternating propulsion current and alternating train controlling current differing in frequency, a train provided with a coil receiving voltages inductively from said trackway currents, an amplifier on said train having an input circuit supplied with voltage by said coil, a condenser and a reactor

50 connected in series across said input circuit, a second condenser interposed in said circuit between said coil and the point at which said reactor is connected with the circuit, a third condenser connected across the terminals of said coil, and train governing means controlled by the output circuit of said amplifier.

55 12. Railway traffic controlling apparatus comprising a trackway, means for supplying thereto alternating propulsion current and alternating train controlling current differing in frequency, a train provided with an amplifier, a plate circuit for said amplifier having two branches each including a condenser and a reactor, the first branch being resonant at approximately the frequency of the third harmonic of said propulsion current and the second branch being resonant at approximately the frequency of said train controlling current, means on said train for impressing across a point in the reactor of said first branch and the grid of said amplifier voltages due to said train controlling current and the third harmonic of said propulsion current, and train governing means controlled by the voltage across the reactor in the second of said plate circuit branches.

60 13. Railway traffic controlling apparatus comprising a trackway, means for supplying thereto alternating propulsion current and alternating train controlling current differing in frequency, a train provided with an amplifier, a plate circuit for said amplifier

65 having two branches each including a condenser and a reactor, the first branch being resonant at approximately the frequency of the third harmonic of said propulsion current and the second branch being resonant at approximately the frequency of said train controlling current, means on said train for impressing across a point in the reactor of said first branch and the grid of said amplifier voltages due to said train controlling current and the third harmonic of said propulsion current, a second amplifier having a grid circuit supplied by the voltage across the reactor in the second of said branches, and train governing means controlled by the plate circuit of said second amplifier.

70 14. Railway traffic controlling apparatus comprising a trackway, means for supplying thereto alternating propulsion current and alternating train controlling current differing in frequency, a train provided with an amplifier, means on said train for supplying the input circuit of said amplifier with voltages due to said train controlling current and the third harmonic of said propulsion current, means associated with said amplifier for regeneratively feeding back into said input circuit current of train controlling frequency and for degeneratively feeding back into said input circuit current of the frequency of the third harmonic of

- 5 said propulsion current, and train governing means controlled by the output circuit 65
of said amplifier.
15. Railway traffic controlling apparatus comprising a trackway, means for supplying thereto alternating propulsion current and alternating train controlling current differing in frequency, a train provided with an amplifier, means on said train for supplying the input circuit of said amplifier with voltages due to said train controlling current and the third harmonic of said propulsion current, means associated with said amplifier 70 for degeneratively feeding back into said input circuit current of the frequency of the third harmonic of said propulsion current, and train governing means controlled by the output circuit of said amplifier. 75
20. 16. Railway traffic controlling apparatus comprising a trackway, means for supplying thereto two alternating train controlling currents of the same frequency but differing in phase as well as alternating propulsion current differing in frequency from the train controlling currents, governing means on a train including an induction motor relay having two stator windings, and apparatus on said train controlled by said trackway 80 currents for supplying said windings with currents of the same frequency and phase relation as said train controlling currents and for preventing the supply to said windings of currents due to said propulsion current. 85
35. 17. Railway traffic controlling apparatus comprising a trackway, means for supplying thereto two alternating train controlling currents of the same frequency but differing in phase as well as alternating propulsion current differing in frequency from the train controlling currents, a train provided with two coils receiving voltages due to said two train controlling currents respectively and also voltages due to said propulsion current, 90 two first stage amplifiers on said train one for each coil, means interposed between each coil and the associated first stage amplifier for supplying to the amplifier voltage due to the train controlling voltage receiving such coil and suppressing the voltage received by the coil due to the fundamental of said propulsion current, two second stage amplifiers on said train one for each first stage amplifier, means interposed between each first stage amplifier and the associated second stage amplifier for supplying the second stage amplifier with voltage due to the train controlling current delivered by the first stage amplifier and suppressing the 95 voltage delivered by the first stage amplifier due to the third harmonic of said propulsion current, and governing means on said train including an induction motor relay having two windings supplied respec- 100
- tively with currents by the output circuits of said second stage amplifiers.
18. Railway traffic controlling apparatus comprising a trackway carrying currents differing in frequency, a train carried coil receiving voltages due to currents in the trackway, governing apparatus on the train supplied with voltage by said coil, a by-pass across said coil resonant at the frequency of one of said trackway currents, and means for tuning said by-pass and said coil to resonance at the frequency of another of said trackway currents. 105
19. Railway traffic controlling apparatus comprising a trackway carrying currents differing in frequency, train carried governing apparatus, and means on the train for supplying said apparatus with a resonant increase of voltage due to current of one frequency in the trackway and with a resonant decrease of voltage due to current of another frequency in the trackway. 115
20. Railway traffic controlling apparatus comprising a trackway carrying currents differing in frequency, train carried governing apparatus, amplifying means on the train for supplying energy to said governing apparatus, and means on the train for supplying said amplifying means with a resonant increase of voltage due to current of one frequency in the trackway and with a resonant decrease of voltage due to the current of another frequency in the trackway. 120
21. Railway traffic controlling apparatus comprising means for supplying the trackway with alternating propulsion current and alternating train controlling current differing in frequency, train carried governing apparatus, amplifying means on the train for supplying energy to said governing apparatus, and means on the train for supplying said amplifying means with a resonant rise of voltage at the frequency of the train controlling current and with a resonant decrease of voltage at the frequency of the propulsion current. 125
22. Railway traffic controlling apparatus comprising means for supplying the trackway with alternating propulsion current and alternating train controlling current differing in frequency, traffic governing apparatus on the train, a coil on the train receiving voltages due to said trackway currents, amplifying means interposed between such coil and said governing apparatus, and a by-pass across said receiving coil tuned to resonance at the frequency of the propulsion current. 130
23. Railway traffic controlling apparatus comprising means for supplying the trackway with alternating propulsion current and alternating train controlling current differing in frequency, traffic governing ap-

paratus on the train, a coil on the train receiving voltages due to said trackway currents, amplifying means interposed between such coil and said governing apparatus, a by-pass across said receiving coil tuned to resonance at the frequency of the propulsion current, and means for tuning said by-pass and said coil to resonance at the frequency of the train controlling current.

10 24. Railway traffic controlling apparatus comprising a trackway carrying currents differing in frequency, a train carried coil receiving voltages due to currents in the trackway, governing apparatus on the train, 15 amplifying means interposed between said coil and said governing apparatus, and a by-pass across said coil resonant at the frequency of one of said trackway currents.

25 25. Railway traffic controlling apparatus comprising a trackway carrying currents differing in frequency, a train carried coil receiving voltages due to currents in the trackway, governing apparatus on the train, 20 amplifying means interposed between said coil and said governing apparatus, a by-pass across said coil resonant at the frequency of one of said trackway currents, and means 25 for tuning said by-pass and said coil to resonance at the frequency of another of said trackway currents.

30 26. Railway traffic controlling apparatus comprising a trackway, means for supplying thereto two alternating train controlling currents of the same frequency but differing 35 in phase as well as alternating propulsion current differing in frequency from the train controlling currents, governing means on the train including an induction motor relay having two stator windings, apparatus on 40 the train including two receiving coils for supplying said stator windings with currents of the same frequency and phase relation as said train controlling currents, and a by-pass across each receiving coil tuned to resonance 45 at the frequency of said propulsion current.

27. Railway traffic controlling apparatus comprising a trackway, means for supplying

thereto two alternating train controlling currents of the same frequency but differing in phase as well as alternating propulsion current differing in frequency from the train controlling currents, governing means on the train including an induction motor relay having two stator windings, apparatus 55 on the train including two receiving coils for supplying said stator windings with currents of the same frequency and phase relation as said train controlling currents, a by-pass across each receiving coil 60 tuned to resonance at the frequency of the propulsion current, and means for tuning each by-pass and the associated receiving coil to resonance at the frequency of said train controlling currents.

65 28. Railway traffic controlling apparatus comprising a trackway, means for supplying thereto alternating propulsion current and alternating train controlling current differing in frequency, a train carried receiving 70 coil, a train carried amplifier having an input circuit connected with said receiving coil, traffic governing means on the train controlled by the output circuit of said amplifier, and a by-pass across said receiving 75 coil tuned to resonance at the frequency of the propulsion current.

80 29. Railway traffic controlling apparatus comprising a trackway, means for supplying thereto alternating propulsion current and alternating train controlling current differing in frequency, a train carried receiving 85 coil, a train carried amplifier having an input circuit connected with said receiving coil, traffic governing means on the train controlled by the output circuit of said amplifier, a by-pass across said receiving coil 90 tuned to resonance at the frequency of the propulsion current, and means for tuning said by-pass and said receiving coil to resonance at the frequency of the train controlling current.

In testimony whereof I affix my signature.

FRANK H. NICHOLSON
